His Attorney

UNITED STATES PATENT OFFICE.

JOHN L. JONES, OF DAYTON, OHIO.

COLLAPSIBLE COPYHOLDER FOR TYPEWRITERS.

Application filed July 16, 1923. Serial No. 651,738.

To all whom it may concern:

Be it known that I, JOHN L. JONES, a citizen of the United States, residing at Dayton, in the county of Montgomery and State of Ohio, have invented certain new and useful Improvements in Collapsible Copyholders for Typewriters, of which the following is a specification.

This invention relates to new and useful improvements in copy-holders for typewriters, and more particularly to a collapsible copy-holder which may be readily attached to, and removed from, any standard typewriter.

15 It is the principal object of my invention to provide a copy-holder which may be easily and firmly secured to a typewriter to support the copy in such a position that it may be plainly visible to the operator.

20 It is a further object of the invention to provide such a copy-holder with means for readily collapsing it upon the machine so that it need not be removed from the latter when it is turned under the movable top of 25 a typewriter desk of the disappearing type.

Other important and incidental objects will be brought out in the following specification, and particularly set forth in the subjoined claims.

30 In the accompanying drawings illustrating one form of embodiment of my invention, Figure 1 is a right side-elevational view of my copy-holder attached to a typewriter. Figure 2 is a similar view of the 35 same in its folded or collapsed position. Figure 3 is a top plan view of the means for clamping the copy-holder to the typewriter. Figure 4 is a front view, partly in section, of the copy-holder. Figure 5 is a 40 plan view of the top of the same. Figure 6 is a left side-elevational view thereof. And Figure 7 is a side elevational view of the means for opening the copy advancing rolls.

45 Throughout the specification and drawings, similar reference characters denote corresponding parts.

Referring to the accompanying drawings illustrating my invention, the numerals 1, 1 50 designate two right-angled clamping members. In the rear end of one of these members there is provided a longitudinal slot 2 into which there freely projects a guiding lug 3 from the corresponding end of the 55 other member. Projecting through a hole in the latter, and through the slot 2 in the

first member 1, is the threaded end of a bolt 4, which receives on its outer end a washer 5 of larger diameter than the slot, and beyond the washer it receives a wing nut 6 by 60 means of which the rear ends of the two clamping members may be drawn in tight engagement with each other.

The front ends of the clamping members 1, 1 are provided with curved portions 7, 7 65 to fit the rear legs 8, 8 of a typewriter 9. Just behind the curved portions 7, 7 of the members 1, 1, there projects through the latter a transverse rod 10. On one end of this rod there is a head 11 which bears against 70 the outer surface of one clamping member, the other end of said rod being threaded to receive a wing nut 12 which may be turned against the outer surface of the other clamping member to draw the curved portions 7, 75 7 of both of them tightly against the legs 8, 8 of the typewriter frame. There are also secured to the clamping members 1, 1 just behind their curved portions 7, 7 angle pieces 13, 13 through which the rod 10 also 80 passes and which are adapted to engage the back surfaces of the rear legs of the typewriter when the wing nut 12 is tightened, to assist the curved portions of the clamping members in firmly gripping them. After 85 the front ends of the clamping members 1, 1 are firmly attached to the legs of the typewriter frame, the wing nut 6 is tightened to firmly connect the rear ends of those clamping members to make them a solid 90 support for the collapsible copy-holder now to be described.

Firmly secured to the rear inner parts of the forwardly projecting portions of the clamping members 1, 1, are two upright supporting members 14, 14. Pivotedly secured to the upper end of each one of these supporting members, by a screw 15 or other suitable threaded element, is an arm 16. These arms may be firmly held in any of 100 their adjusted positions by wing nuts 17 on the outer ends of the pivot screws 15. (See Figures 1 and 2.)

The arms 16, 16 terminate at their upper ends in short horizontal portions 18, 18. 105 Secured upon the top of each horizontal portion 18 is a forwardly projecting, elongated bearing member 19. Each bearing member 19 comprises a metal block which, in its rear end, contains a transverse hole to receive one 110 end of a roller spindle 20. In front of this hole the bearing member is cut away to leave

a front flange 21 between which and the rear portion of said member, one end of a roller spindle 22 is free to travel.

The front face of the rear portion of each bearing member 19 is concaved to receive the roller spindle 22, the latter being maintained in said concaved face by a concaved slide 23 from which there projects forwardly, through a hole in the flange 21, a pin 24 that is surrounded between the flange and the slide by a helical compression spring 25. To the top of the bearing member there is applied a cover plate 26 which holds the spindle 22 and the slide 23 within it during their travel. (See Figures 5 and 6.)

Mounted on the spindles 20 and 22 are rubber rollers 27, 27 which are adapted to receive between them a copy sheet (not shown) for the use of the operator. The roller 22 is drawn away from the roller 20 against the compression of the spring 25, by the following means to insert or remove a copy sheet. Loosely projecting through holes in the arms 16, 16 below the bearing members 19, 19, is a rod 28. The latter also passes through an upright metal piece 29 that is secured at its lower end to a boss 30 which projects inwardly from the lower portion of the right arm 16. (See Figure 4.)

Tightly secured to the rod 28 between the right arm 16 and the metal piece 29, is an arm 31 whose top end is concaved to fit the roller spindle 22. A similar arm 32 is fixedly attached to the rod 28 near the left supporting arm 16. Fixedly secured to the extreme right end of the rod 28 is an operating lever 33 which, when depressed by the operator, will move the roller spindle 22 outwardly against the compression springs 25, 25 to provide between the rollers 27, 27 a space of sufficient width to easily receive the copy sheet, which is advanced by the means now to be described.

Fixedly secured to the outer end of the roller spindle 20 above the lever 33, is a ratchet disc 34 which is adapted to be engaged by a pawl 35 pivotally secured by a pin 36 to one end of a lever 37. Attached to the pawl-carrying end of the latter is a spring 38 which is adapted to press against the rear end of the pawl to maintain its nose portion in engagement with the teeth of the ratchet disc. Pivotally secured to the other end of the lever 37 is the horizontal end of a vertical rod 39 which is pivotally secured at its lower end, by a pin 40, to the upper end of a vertical rod 41. The latter passes downwardly through an eye-piece 42 secured to the arm 16, being connected at its lower end by a pin 43 to one end of a bell-crank lever 44 that is pivotally secured by a pin 45 to the rear part of the forwardly projecting portion of the right clamping member 1. (See Figures 1 and 2.)

The lower end of the bell-crank lever 44

is connected by a link 46 to the upper end of another bell-crank lever 47 which is pivotally secured by a pin 48 to the lower end of a vertical supporting piece 49 that depends from the right clamping member 1. The lower end of the bell-crank lever 47 is connected by a link 50 to the rear end of a horizontal lever 51 which is pivotally secured by a screw 52 to the front end of a curved angle member 53 that depends from the front end of the right clamping member 1. (See Figures 1 and 2.)

Pivotally secured by a screw 54 to the front end of the lever 51, is an operating lever 55 which carries on its front end a button 56 for engagement by a finger on the operator's hand. The rear end of the lever 55 is notched, as at 57, to engage a screw 58 on the outer end of the lever 51 to make the latter and the lever 55 one continuous lever for actuation by the operator to turn the rollers 27, 27 through the ratchet mechanism, levers and links just described. (See Figures 1 and 2.)

Projecting rearwardly from the lower part of the supporting element 53 is an eyelet arm 59 through which there projects downwardly, a threaded pin 60 having a knurled head 61. The lower end of this pin is in the path of upward movement of the rear end of the lever 51, so that the number of spaces the rollers 27 are turned when the lever 55 is depressed, may be controlled by adjusting the height of the pin 60.

After each depression of the lever 55, it will be returned to its normal position by a helical spring 62 connected between the front end of the lever 37 and the right arm 16. (See Figure 1.) This spring not only returns the lever 55 to its normal position through the levers and links hereinbefore described, but it also draws the pawl 35 counterclockwise over the teeth of the ratchet disc 34 to a point where its nose portion will engage the disc to turn it the desired number of spaces when the lever 55 is again depressed by the operator.

Firmly secured to the right bearing member 19, are the ends of two rods 63, 63 which project upwardly and then horizontally over the rollers 27, 27 respectively, through holes in a bracket piece 64 on the left bearing member 19, to act as top guides for the copy sheet which passes between the rollers. The guide rods 63, 63 pass loosely through the bracket piece 64, and the ends of the roller spindles 20 and 22 pass freely through the left bearing member 19, so that the arms 16, 16 may be easily spread apart or moved toward each other when the clamping members 1, 1 are being applied to different width typewriters. (See Figures 1 and 2.)

In operation, when it is desired to insert a copy sheet between the rollers 27, 27, the lever 33 is depressed by a button 65 which it

carries on its front end, to the position shown in dotted lines in Figure 7, for the purpose of withdrawing the front roller 27 a sufficient distance from the rear one to permit the insertion of the copy sheet between them. Then, when the pressure of the finger is released from the lever 33, the springs 25, 25 will force the roller spindle 22 inwardly to carry the front roller into a sufficiently firm contact with the copy sheet and rear roller, that when the latter is turned by the ratchet mechanism, it will advance the copy sheet the desired distance. As stated before, this distance will be determined by the position of the stop pin 60 which limits the upward movement of the rear end of the lever 51 to which the lever 55 is pivotally connected.

When it is desired to collapse the copy-holder so that it may be carried into a desk by its movable support without interfering with the stationary parts of the desk, the wing nuts 17, 17 are loosened to permit the arms 16, 16 to be turned toward the outer end of the lever 55 until the bearing members 19, 19 engage the top of the machine, as shown in Figure 2. The outer end of the lever 55 is then turned about its pivot screw 54, toward the arms 16, 16, as is also shown in Figure 2. The typewriter is now free to be carried into a desk by its movable support, without fear of the copy-holder interfering with its inward movement. Furthermore, when the copyholder is removed from the typewriter, it may be collapsed as above described for storage in a small space, or for the purpose of being easily carried from place to place.

Having described my invention, I claim:

1. A copyholder for typewriters, comprising a pair of clamping members for attach-

ment to a typewriter and to each other, upright supporting members secured to the clamping members, arms pivotally secured to the upright supporting members, feed rollers supported by the upper ends of said arms, a ratchet for turning said rollers, a lever, a pawl carried by one end of said lever to actuate said ratchet, a rod depending from the other end of said lever to a point near the point of connection between the adjacent arm and its supporting member, and means compressible near the typewriter keys, connected to the lower end of said rod for the purpose specified.

2. A copy-holder for typewriters, comprising a pair of clamping members for attachment to a typewriter and to each other, upright supporting members secured to the clamping members, arms pivotally secured to the upright supporting members, a pair of feed rollers supported by the upper ends of said arms, a ratchet for turning said rollers, a lever, a pawl carried by one end of said lever to actuate said ratchet, a rod depending from the other end of said lever to a point near the point of connection between the adjacent arm and its supporting member, a horizontal, jointed operating lever, and linkage connected between the inner end of said collapsible lever having a pressure end near the typewriter keys and the lower end of the depending rod, the latter and said arms adapted to be turned toward the outer end of the jointed operating lever, which is also adapted to be moved toward them to collapse the copy-holder.

In testimony whereof I have hereunto set my hand this 14th day of July, 1923.

JOHN L. JONES.
